(57) **CLAIM**

The ornamental design for a bottle, substantially as shown and described.

DESCRIPTION

FIG. 1 is a perspective view of the bottle of the present invention;

FIG. 2 is a top plan view of the bottle of FIG. 1;

FIG. 3 is a bottom plan view of the bottle thereof;

FIG. 4 is a front elevational view of the bottle thereof;

FIG. 5 is a side elevational view of the bottle thereof; and,

FIG. 6 is a rear elevational view of the bottle thereof.

The solid line at the top inside edge of the pour spout lip is the boundary of the claim.

The broken lines shown in FIGS. 1 & 4-6 are for illustrative purposes only and form no part of the claimed design.

1 Claim, 1 Drawing Sheet**FIG. 1.**

FIG. 2.

FIG. 3.

FIG. 4.

FIG. 5.

FIG. 6.
